(57) **CLAIM**

The ornamental design for a golf ramp, as shown and described.

DESCRIPTION

FIG. 1A is a top front left perspective view of the golf ramp of the present invention;

FIG. 1B is a partial enlarged view taken along line 1B of FIG. 1A;

FIG. 2 is a top front right perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is an environmental view of the golf ramp stored in a golf bag.

The bottom view of the golf ramp has no ornamental aspects and is not shown.

The portions of the golf ramp illustrated in broken lines form no part of the claimed design.
